DESIGN FOR A SCALE

Stan L. Hanssen, Chicago, Ill., assignor to Hanson Scale Company, Chicago, Ill., a corporation of Illinois

Application April 14, 1939, Serial No. 84,274

Term of patent 14 years

To all whom it may concern:

Be it known that I, Stan L. Hanssen, a citizen of the United States, residing at Chicago, in the county of Cook and State of Illinois, have invented a new, original, and ornamental Design for Scales, of which the following is a specification, reference being had to the accompanying drawing, forming a part thereof, and in which:

Figure 1 is a front view of a scale showing my new design;

Figure 2 is a back view of the scale shown in

I claim:

The ornamental design for a scale, as shown.

STAN L. HANSSEN.
